United States Patent Office

Des. 208,291
Patented Aug. 15, 1967

208,291

URINAL

Lawrie G. McIntosh, Islington, Ontario, Canada, assignor,
by mesne assignments, to The International Nickel Company, Inc., New York, N.Y., a corporation of Delaware

Filed Mar. 7, 1966, Ser. No. 1,500

Term of patent 14 years

(Cl. D4—5)

FIG. 1

FIG. 3

FIG. 4

FIG. 2

FIGURE 1 is a front perspective view of a urinal showing my new design;

FIGURE 2 is a side elevation view of the urinal shown in FIGURE 1;

FIGURE 3 is a top plan view; and
FIGURE 4 is a front elevation view.

I claim:

The ornamental design for a urinal, substantially as shown.
